The ornamental design for a operation device for a magnetic resonance tomography diagnosis apparatus, as shown and described.

DESCRIPTION

FIG. 1 is a front, top and left side perspective view of a operation device for a magnetic resonance tomography diagnosis apparatus, showing my new design;

FIG. 2 is a top view thereof;

FIG. 3 is a front view thereof;

FIG. 4 is a right side view thereof, the left side view being symmetrical;

FIG. 5 is a rear view thereof;

FIG. 6 is a bottom view thereof; and,

FIG. 7 is an enlarged cross-section view thereof, taken along the line 7-7 in FIG. 3 with its internal mechanisms omitted. The broken lines shown in FIG. 7 are for environmental purposes only and form no part of the claimed design.
